INFANT'S DRESSING TABLE

Raymond G. Pierson, 120 Simson St.,
Bedford, Pa. 15522

Filed Oct. 29, 1973, Ser. No. 410,518

Term of patent 7 years

Int. Cl. D6—04

U.S. CL. D6—5

FIG. 1

FIG. 2

FIG. 3

FIG. 1 is a front, top and right side perspective view of an infant's dressing table showing my new design;

FIG. 2 is a left side elevational view;

FIG. 3 is a top plan view; and

FIG. 4 is a rear elevational view.

I claim:

The ornamental design for an infant's dressing table, substantially as shown and described.
